UNITED STATES PATENT OFFICE.

WILLIAM A. PERRY, OF ST. LOUIS, MISSOURI.

FUSIBLE LINK FOR SPRINKLER-HEADS.

1,208,200.

Specification of Letters Patent. Patented Dec. 12, 1916.

Application filed January 31, 1916. Serial No. 75,420.

To all whom it may concern:

Be it known that I, WILLIAM A. PERRY, a citizen of the United States, residing at St. Louis, State of Missouri, have invented 5 certain new and useful Improvements in Fusible Links for Sprinkler-Heads, of which the following is a full, clear, and exact description, reference being had to the accompanying drawings, forming a part hereof.

10 My invention has relation to improvements in fusible links for sprinkler-heads; and it consists in the novel features of construction more fully set forth in the specification and pointed out in the claims.

15 The object of my invention is to provide a fusible link which will readily break down upon the application of heat, owing to the melting of the fusible component, but which will not break down under pressure, or by 20 jarring, as is the case with the links in use.

A further object of my invention is to provide a link, the respective parts of which will separate instantly when the fusible component is melted, and one that will not 25 bind or stick as often happens with the links in present use.

Other advantages will be better apparent from a detailed description of my invention, in which—

30 Figure 1 is a side elevation of a sprinkler head with my improved link applied thereto; Fig. 2 is an edge view of the link; Fig. 3 is a face view of the link with a part of the solder broken away to disclose the center ball, and a part removed to show one of the hooks; Fig. 4 is a vertical cross-section on the line 4—4 of Fig. 3; Fig. 5 is a section similar to Fig. 4, the solder, however, having been melted away from the link components, and one of said components being 40 shown dotted as it is being withdrawn from the other; and Fig. 6 is an enlarged cross-section on the line 6—6 of Fig. 3.

45 Referring to the drawings, H represents a sprinkler head and T the struts thereof held in position by the fusible link L. The link L is the subject-matter of my invention and consists of the components or sections 1, 1', and a rolling fulcrum or ball 2 presently to be described in detail. At one 50 end of the section or component 1, the corners are bent over so as to form the hooks h, h, the remaining portion of the member between the hooks constituting a tongue t, said tongue being provided with an opening o, adapted to receive one of the struts

T. The component 1' is also bent over at the corners of one end thus forming the hooks h', h', and leaving a tongue t' projecting outwardly between the hooks in 60 which is an opening o' likewise for receiving one of the struts T. Each of the sections 1, 1', is perforated substantially in the center by openings O, O', respectively, the edges of said openings being concaved 65 or dished so as to furnish a snug seat for the ball 2, which couples the sections 1, 1', and normally restrains them against longitudinal displacement. The link sections are provided with recesses r, r', opposite the 70 openings o', o, respectively, to provide clearance for the struts T, T, when the link is assembled and ready for use.

All of the parts having been described, let us now see how they are assembled so 75 as to constitute the fusible link. The sections 1, 1', have their inner faces f, f', respectively coated with a suitable soldering material m, the ball 2 also being coated with solder, after which the ball 2 is inserted into 80 the openings O, O', and held between the link sections, the soldered or "tinned" faces being brought together, and the hooks h, h, h', h', projecting beyond the edges of the sections 1', 1, respectively. While the sections and ball 2 are thus held together, they are brought in contact with heat sufficient to melt the solder on the members 1, 1', and ball 2, which, upon cooling, causes the members and ball to adhere and unites the parts 90 into an integral link. The next step is to solder the overlapping hook of one member to the edge of the other member by drops of solder s, s, (Fig. 4). The solder is worked into the spaces e, e, between the 95 hook of one section and the opposite section (as shown in Figs. 4 and 6), for a purpose presently to be seen. When the link is in place between the struts, considerable pull is exerted on it, and if only the solder m 100 was relied on to prevent the sections from separating, the continuing pull exerted on the sections by the struts would soon force the sections apart and allow the sprinkler head to "go off", which is the very thing 105 that it is intended to overcome. The ball 2 takes this strain off the solder m and transmits it to the sections, said ball operating as a coupling in binding these sections together. However, when the solder has been 110 melted the link sections are free to separate, the rolling fulcrum or ball 2 permitting a

compound movement of the sections, to wit, a longitudinal movement between the sections and a lateral separating movement, fully indicated by dotted position and arrows Fig. 5. If the pull on the link sections is excessive there may be a tendency for the sections to separate from each other, laterally as they roll on the ball; and as a precaution against this separation (indicated by the arrow Fig. 4) the spaces e, e' , are filled with solder s , which acts as an anchor, and imparts any lateral strain to the hooks, h, h', h', h' , against which the solder abuts, (Figs. 4 and 6). However, the hooks h, h', h', h' must not all project in front of the edges of the sections 1, 1', since one of the sections must pass the adjacent hooks when the links separate. In the present case the section 1 is allowed to pass the hooks h', h' when the sections are being pulled apart (Fig. 5 dotted position). It is apparent that the only way for the sections to separate is for the solder to be melted first, after which the members can roll past each other on the ball 2, this movement being permitted by the clearance between the section 1, and hooks h', h' .

The solder composing the anchor s is to be distinguished from the solder m between the link sections, as the former serves as an abutment between the adjacent ends of the link sections restraining lateral movement on the part of either link section, while the latter merely holds the sections together by virtue of its adhesive force.

It is obvious that the present invention is

susceptible of modifications without in any wise departing from the spirit of the invention.

Having described my invention, what I claim is:

1. In a fusible link, a pair of sections placed face to face in parallel relation, a coupling ball traversing said pair of sections, corner hooks on one edge of each of said sections projecting over the free edge of the adjacent section tongue formations between the hooks, a fusible substance interposed between each of said hooks and edge of the adjacent section, and a fusible substance holding the sections in fixed relation.

2. In a fusible link for sprinkler heads, a pair of sections placed face to face in substantially parallel relation, registering openings substantially in the center of said sections, concave walls bounding said openings, a ball traversing the openings and seated on the concave walls, the latter operating to prevent the ball from becoming displaced, corner hooks on one edge of each of said sections projecting over the free edge of the adjacent section tongues between the hooks, a fusible substance interposed between the ends of the hooks and said free edge, and a fusible substance holding the sections and ball in fixed relation.

In testimony whereof I affix my signature, in presence of two witnesses.

WILLIAM A. PERRY.
